M. Page.
Turpentine Still.

No 9752

Patented May 24, 1853.

UNITED STATES PATENT OFFICE.

MADISON PAGE, OF WILLIAMSBURG, NEW YORK, ASSIGNOR TO SAM'L. W. HAWES, OF CHELSEA, MASSACHUSETTS.

IMPROVEMENT IN PROCESSES OF DISTILLING ROSIN-OIL.

Specification forming part of Letters Patent No. 9,752, dated May 24, 1853.

To all whom it may concern:

Be it known that I, MADISON PAGE, of Williamsburg, in the county of Kings and State of New York, have invented certain new and useful Improvements in the Manufacture and Refining of Rosin-Oil, which consists in the introduction of steam therein; and I do hereby declare that the following is a full, clear, and exact description thereof, reference being had to the accompanying drawing, which forms a part thereof.

My method of producing the oils from rosin for various purposes is substantially as follows: I employ a still of any convenient shape, one form of which is shown in Figure 1, *a*, which is a vertical section through its center. The head and goose-neck *b* are of ordinary form, connecting with a condensing-worm, *d*. The still is also furnished with man-holes and other devices usually found in such structures. To determine with exactness the degree of heat employed in the process of distillation in these high temperatures, the heat is calculated by the heat of the steam driven off in a manner well known. Into that part of the still above the material to be distilled a steam-pipe, *e*, is introduced. Its end is perforated, and it communicates with a steam-boiler, by which it is supplied. This steam should be so introduced as not to be driven in contact with the melted rosin, but only with its vapor above the body of the still, and in the figure it is for this purpose placed in the goose-neck at *f*.

The apparatus as thus constructed is used in the following way: The first process is to extract the acid from the rosin, next the naphtha, and lastly the oil, and to procure them each separate from the other. I first charge the still with rosin to about two-thirds of its capacity, more or less. The fire is then kindled under it, and I gradually increase the heat till the moisture is driven off. As the heat rises the rosin first swells, and is violently agitated in the first stages of manufacture and until the aqueous matter is expelled. I therefore, during this part of my process, detach the worm from the goose-neck, as there is some danger of an explosion if the still is closed, in case of an overflow. After all the aqueous vapor is expelled, the heat is still

further raised, and the acid is thus discharged. When this ceases to flow, the steam is admitted through the pipe *e*, and the worm is connected with the goose-neck, the heat being still kept up to the point where the naphtha will pass over with the steam and be discharged in a condensed state from the worm. This temperature must be kept up till the naphtha ceases to flow, or, rather, has all been discharged. This is ascertained by its quantity, which is about fifteen per centum of the rosin. When the naphtha ceases to flow, the heat is again raised in the still (the steam being at the same time freely admitted through pipe *e*) till the oil begins to come over mingled with the steam, and, being condensed in the worm, runs into a proper receiver. The temperature should be maintained at about the point where the oil first begins to come over till it ceases to flow, when the heat is again raised still higher, and a second portion is distilled over, after which a third increase of heat takes place and is continued till all the oil is discharged from the rosin. This will be found to be about sixty-two and a half per centum of the rosin put into the still. The residuum—a pitchy substance—is then drawn off from the still, which is thus prepared for a new charge.

To make an oil for lubricating purposes, I take the above-named oils distilled at the lowest temperature and redistill it in the same manner as it was at first distilled, introducing the steam freely, as before described, by which the oil is, so to speak, washed while in a vaporous state, and the acid, &c., removed more perfectly than in any other way, by which it is fitted for lubricating purposes. For currier's oil I usually take that distilled at the next highest temperature, which I redistill in the same way with steam, and for the same purpose, and the oil last distilled being the purest, I employ, after redistilling and boiling, for painters' purposes, the odor from the naphtha, acid, &c., being removed by the steam.

Having thus fully described my purposes, it will be proper to remark that the reason for and advantage of my process of introducing steam is to have the purifying effect of it without danger and in a practicable manner, for moisture commingled with melted rosin pro-

duces dangerous effects, causing it to swell, boil over, explode, and burn up. It must therefore be carefully kept out of the rosin; but it is of the greatest importance in purifying the product, provided it can be introduced without danger. The mode of doing this is my device, which is by the introduction of a jet of steam into the vapor rising from the still. If water were introduced into the rosin, it would all be driven off before it could have any effect, and would increase the trouble and expense of expelling the aqueous matter already in the rosin, and should steam be introduced into the mass highly heated an explosion must take place; but by my arrangement all danger is avoided and the full advantages of steam secured.

Having thus fully set forth my invention,

what I claim therein as new, and for which I desire to secure Letters Patent, is—

The employment, in the manner and for the purposes described, in the manufacture of rosin-oils of different qualities, of redistilling the same, and purifying it, substantially as herein set forth, the introduction of the steam into the commencement of the goose-neck, above the rosin in the still, so that the vaporized oils from the rosin will pass through and be commingled with said steam in their passage to the worm for condensation, for the purposes of purification, &c., as above fully set forth.

MADISON PAGE.
